SIGNALING SYSTEM

Robert A. Clark, Jr., Chicago, Ill.

Application February 17, 1944, Serial No. 522,742

7 Claims. (Cl. 179—84)

1

The present invention relates to signaling systems and more particularly to improved apparatus for discriminating between two different signals which may be non-concurrently transmitted over a signal channel of a telephone or similar signaling system.

In conventional telephone systems it is usually necessary that each voice channel be utilized not only for voice signal transmission, but also for the transmission of supervisory signals, such for example as ringing signals, flashing recalls signals and the like. Further, in long lines networks, utilizing repeaters for voice current gain, it is highly desirable to use alternating supervisory signals having a fixed frequency within the voice frequency range to provide the desired signal indications. This has previously been accomplished by modulating a voice frequency carrier at a low frequency, and utilizing the low frequency component of the signal for supervisory signaling purposes. It has been found, however, that with such arrangements, voice signals traversing the signals channel may produce a false response of the supervisory signal detecting equipment, if the level of voice signal transmission is sufficiently high.

It is an object of the present invention, therefore, to provide improved and exceedingly reliable methods and apparatus for discriminating between voice and supervisory signals which may be transmitted over a voice signal channel.

More generally stated, it is an object of the present invention to provide improved methods and apparatus for discrimination between a first signal having different frequencies within a band and a second signal having a fixed frequency within the band when the signals of different types are non-concurrently received over the same signal channel.

According to a further object of the invention, those components of a received first or voice signal which have frequencies other than the fixed frequency of the second or supervisory signal are utilized to prevent the apparatus for detecting the second or supervisory signal from responding to a component of a received first signal which has the same frequency as the second signal.

In accordance with a further and more specific object of the invention, a four terminal bridge circuit, which is balanced only at the fixed frequency of the second or supervisory signal, is utilized in discriminating between the signals of different characters.

It is still another object of the invention to

2

provide an improved circuit network which is simple in arrangement and is positive and reliable in its operation to discriminate between a signal having different frequencies within a given band and a second signal having a fixed frequency within the given band.

The invention, both as to its organization and method of operation, together with further objects and advantages thereof, will best be understood by reference to the specification taken in connection with the accompanying drawings, in which Figs. 1 and 2, when laid end to end in the order named, illustrate a portion of a telephone system having embodied therein a signal discriminating network characterized by the features of the present invention.

Referring now to the drawings, the equipment there illustrated may be provided in the toll exchange of a metropolitan central exchange area or alternatively may be located in an isolated private branch exchange which is connected with a central exchange area by means of trunks requiring voice current amplification for satisfactory communication thereover. In brief, this equipment comprises an operator switchboard 10 having a jack 10a, a ringing signal in the form of a drop 10c, and a pad switching key 10d associated with a signal channel to a distant office. This channel is divided within the exchange into an incoming signal channel 11 and an outgoing signal channel 12 in order to permit suitable filter and amplifier facilities to be provided for insuring high level, high fidelity transmission between the switchboard 10 and the distant office. If carrier transmission is utilized between the illustrated exchange equipment and the distant office, the bracketed terminals of the two signal channels 11 and 12 will of course extend to conventional composite equipment through which they are coupled to a specified carrier channel. On the other hand, if a two conductor trunk is utilized to connect the illustrated exchange equipment with the distant office, the identified channels will of course be coupled to the trunk through a conventional hybrid system. Within the exchange, the two channels 11 and 12 are coupled to a two-way link extending to the call and answer jack 10a by means of a conventional hybrid system 14 and pad or transmission loss network 13, both of which are entirely conventional in arrangement. The network 14 is, of course, utilized to determine the level of voice current transmission over a connection set up by way of the illustrated equipment. The impedance of the network 13, as combined with the

equivalent impedance of an operator cord circuit connected with the tip and ring contacts of the jack 10a, is balanced by means of a balancing network 15, thereby to effectively isolate the two channels 11 and 12 and thus minimize the transmission of signals from the channel 11 to the channel 12 through the hybrid system 14. Switching relays 60 and 70 arrange for control by the pad key 10d are respectively provided for switching in and out signal loss resistors within the network 13 and correspondingly changing the impedance of the balancing network 70 to maintain the hybrid system 14 in a balanced condition. A filter and amplifier network 9, which may be entirely conventional in character, is provided in the outgoing signal channel 12 for the purpose of raising the level of voice transmission to the desired value. Similarly, the incoming signal channel 11 includes an amplifier and filter network 16 and a final audio amplifier stage 17, arranged in tandem in the order named. The final amplifier stage 17 includes an electron discharge tube 18 provided with an output circuit which is directly coupled to the input terminals of the hybrid system 14.

For the purpose of discriminating between voice signals and supervisory signals traversing the incoming signal channel 11, a bridge circuit indicated generally at 19 is coupled to this channel through an adjustable potentiometer resistor 22 which shunts the channel at the output side of the tube 18 and is paralleled by a filter condenser 23. More specifically, the bridge circuit 19 includes a voltage step up transformer 21 having a primary winding 21a bridged across an adjustable portion of the potentiometer resistor 22 by means of the wiper 22a which is adjustable along this resistor. The transformer 21 also includes a secondary winding having a tapped midpoint 19a, such that equal voltages are developed in the two sections 21b and 21c thereof when the primary wind 21a is energized at any frequency within the audio frequency range. The two identified sections of the transformer secondary winding respectively comprise two legs of the described bridge circuit. A third leg of the bridge circuit is made up of a parallel resonant circuit 24 which comprises the shunt connected inductance and capacitance elements 24a and 24b. This resonant circuit is tuned exactly to the fixed frequency within the audio frequency range at which supervisory signals are transmitted to the input side of the amplifier and filter network 16. Thus if a fixed frequency of 1500 cycles is to be utilized as the supervisory signaling frequency, the circuit 24 is tuned exactly to this frequency. For the purpose of matching the terminal impedance of the circuit 24 at this frequency, the fourth leg of the bridge circuit is made up of an adjustable resistor 25 having a wiper 25a movable therealong for the purpose of varying the encircuited portion of the resistor. It will thus be apparent that the bridge circuit 19 comprises four legs 21b, 21c, 24 and 25 having four terminals 19a, 19b, 19c and 19d, and that a voltage appearing upon the incoming signal channel 11 is equally impressed upon the two legs 21b and 21c thereof through the inductive coupling between these legs and the primary winding 21a. It will also be understood that at resonance the impedance of the tuned circuit 24 is substantially resistive and hence may be entirely balanced by suitable adjustment of the wiper 25a along the resistor 25.

In order to detect a supervisory signal appear-

ing upon the incoming signal channel 11 and impressed upon the bridge circuit 19 in the manner just explained, detecting means are provided which comprise a three electrode thermionic tube 20 and a signal repeating relay 40 shunted by a delay release condenser 40a. More specifically, the output circuit of the tube 20 includes the winding of the relay 40 and the upper part of a voltage dividing resistor 29. The input electrodes of the detecting tube 20 are bridged across the resonant circuit 24 in series with a decoupling resistor 28a, a biasing resistor 27 and a source of biasing potential represented by the voltage appearing across the section 29a of the voltage dividing resistor 29. With this arrangement and as will appear later, when the bridge circuit 19 is energized at the particular frequency of 1500 cycles at which it is balanced, the voltage drop across the resonant circuit 24 is detected by the tube 20 and utilized to effect operation of the signal repeating relay 40. For the purpose of utilizing a received voice signal to develop a bias voltage which may be applied to the tube 20 to prevent the relay 40 from operating, a biasing network is provided which is coupled to the terminals 19a and 19d of the bridge circuit, and is utilized to develop a bias voltage across the biasing resistor 27. More specifically, this network comprises a transformer 26 having a primary winding 26a bridged between the terminals 19a and 19d, and a secondary winding 26b which is bridged across the biasing resistor 27 in series with the space current path of a diode rectifier 30. The resistor 27 is shunted by a smoothing condenser 28 which is utilized to maintain a direct voltage across the resistor 27 when the primary winding 26a of the transformer is energized.

In the illustrated arrangement of the equipment, incoming supervisory signals are utilized only for the purpose of controlling the drop 10c associated with the jack 10a. To this end, the relay 40 is arranged directly to control a ringing relay 50 having the function of cutting off the pad network 13 from the jack 10a, opening the incoming signal channel 11, and connecting the tip and ring contacts of the jack 10a to the source of ringing current which is provided in the exchange. In this regard it will be understood that the exchange in which the illustrated equipment is located includes a conventional exchange battery having a grounded positive terminal and a negative terminal connected to each of the illustrated relay terminals identified by the negative polarity sign.

Briefly to consider the operation of the above described equipment, it will be understood that when this equipment is seized in the distant office on a call to the operator switchboard 10, a ringing signal of the fixed frequency selected for supervisory signaling and originating at the distant end of the connection is impressed upon the input side of the signal channel 11. More specifically, this signal has a frequency exactly equal the particular frequency to which the resonant circuit 24 is tuned. It is amplified through the network 16 and the final amplifier stage 17 and appears across the potentiometer resistor 22. That portion thereof which appears across the lower part of the resistor 22 serves to energize the winding 21a, thereby to produce equal voltages across the two legs 21b and 21c of the bridge circuit 19. Since at the particular frequency indicated, the resistive impedance of the resonant circuit 24 is matched by the resistance of the potentiometer

resistor 25, substantially no voltage appears between the bridge circuit terminal 19a and 19d, so that the voltage input to the biasing network comprising the diode rectifier 30 is negligible. The alternating voltage appearing across the resonant circuit 24 is obviously impressed between the input electrodes of the detector tube 20 and during the alternate half cycles thereof opposes the bias voltage appearing across the resistor section 29a, so that the current flow through this tube and the winding of the signal repeating relay 40 is substantially increased. As a result, the relay 40 is caused to operate. In operating, this relay opens its contacts 42 to interrupt the path normally short circuiting the winding of the ringing relay 30, and closes its contacts 41 to energize the relay 50 from the exchange battery. The relay 50 upon operating, opens its contacts 51 to interrupt the connection between the hybrid system 14 and the final amplifier stage 17 of the incoming signal channel 11. At its contacts 52 and 54, the relay opens the connection between the jack 10a and the pad network 13. At its contacts 53 and 55, the relay 50 completes a circuit for energizing the winding of the drop 10c from the ringing current source. When thus energized, the drop 10c is actuated to provide an indication that an incoming call has been routed to the jack 10a which should be answered.

Upon termination of the ringing signal appearing at the input side of the signal channel 11, the bridge circuit 19 is obviously de-energized, permitting the bias voltage across the resistor section 29a to so reduce the space current flow through the detector tube 20 as to effect the release of the signal relay 40. Upon restoring, this relay opens its contacts 41 to deenergize the relay 50 and closes its contacts 42 to recomplete the path for short-circuiting the winding of the relay 50, thereby to render the latter relay slow to release. After a short interval, the relay 50 restores and opens its contacts 53 and 55 to deenergize the winding of the drop 10c. At its contacts 51, the relay 50 recomplete the connection between the hybrid system 14 and the final amplifier stage 17. At its contacts 52 and 54 the relay 50 recomplete the connection between the jack 10a and the pad network 13. Thus the illustrated equipment is conditioned for two-way voice communication over a connection set up by way of the jack 10a.

In order to extend the call from the jack 10a to the desired point, the operator attending the switchboard 10 or that portion thereof at which the identified jack is provided, may insert the answer plug of her cord circuit in the jack 10a to establish a connection between her cord circuit and the calling operator. Incident to this operation, the jack contacts 10b and 10c are opened to disconnect the winding of the drop 10c from the two sides of the signal channel. Voice signals originating at the distant end of the connection and appearing at the input side of the signal channel 11 are amplified through the network 16 and the final amplifier stage 17, and are transmitted through the hybrid system 14 and the pad network 13 to the receiver of the operator's head set for reproduction. In this regard it will be understood that the hybrid system 14 acts to prevent signal energy transfer from the channel 11 to the channel 12, thereby to eliminate any possibility of singing. Voice currents originated by the operator handling the call at the switchboard 10, are similarly transmitted through the pad network 13, the hybrid system

14 and the amplifier network 9 for transmission to the distant operator. Thus a two-way communication channel is set up between the calling and answering operators over which instructions may be transmitted to the answering operator for the extension of the call. The manner in which the call may be further extended to the desired destination is exactly the same as that followed in conventional manual office or toll office practice. In this regard it is pointed out that depending upon the destination of the call, a variable amount of voice current gain may be required for satisfactory communication between the calling and called parties. Thus if the call is to be extended over a long high loss line, considerable voice current gain may be required in the illustrated equipment to insure an adequate level of signal reproduction at the calling and called ends of the connection. In such case the pad key 10d may be operated for the purpose of energizing the two switching relays 60 and 70, thereby to cut out the transmission loss pads in the network 13 and to correspondingly change the impedance of the network 15 to provide for a continued balance of the hybrid system 14. If, on the other hand, the call is to be extended over a short line having good voice current transmission characteristics such that only the normal amount of signal gain through the illustrated equipment is required, the loss pads of the network 13 are retained in the circuit.

In this regard it will be understood that voice signals originating at the distant end of the connection and appearing at the input side of the signal channel 11 may comprise different composites of all frequencies within the audio frequency range. The received voice signals may or may not include a component having the particular frequency to which the resonant circuit 24 is tuned. Moreover, any received voice signal having the particular frequency to which the resonant circuit 24 is tuned will always be accompanied by other components having frequencies differing from this particular frequency. Also, at all frequencies within the voice frequency range other than the particular frequency to which the circuit 24 is tuned, the terminal impedance of the resonant circuit 24 is different from that of the resistor 25. Thus, the bridge circuit 19 is unbalanced at such frequencies, so that a voltage is developed between the terminals 19a and 19d thereof. It will be understood, therefore, that so long as voice current transmission over the channel 11 continues, a substantial voltage is impressed upon the primary winding 26a of the transformer 26. This voltage appears in increased magnitude across the secondary winding 26b and is rectified by the diode rectifier 30 to appear as a direct current biasing voltage across the biasing resistor 27. Moreover, the direction of current flow through the diode 30 is such that the voltage developed across the resistor 27 is additive with respect to the voltage across the resistor section 29a, whereby the total bias voltage impressed between the input electrodes of the tube 20 through the inductance element 24a is substantially increased. This increased bias voltage as applied to the detector tube 20 opposes the voltage appearing across the resonant circuit 24, thereby to prevent the relay 40 from operating even though a voice signal component of the particular frequency to which the circuit 24 is tuned appears at the input side of the signal channel 11. Thus the relay 40 is positively prevented

from operating when the channel 11 is being utilized for voice signal transmission.

After a connection has been set up between two substations through the illustrated equipment in the manner explained above, it may be released under the control of the calling operator and the operator handling the call at the switchboard 10 in an entirely conventional manner. Further, the manner in which calls may be routed from the switchboard 10 through the illustrated equipment to the distant office is entirely conventional and will be readily apparent to those skilled in the art. In this regard it is pointed out that in the interests of simplifying the disclosure, the equipment for transmitting supervisory signals from the switchboard 10 through the illustrated circuit equipment to the distant office has not been illustrated in the drawings.

From the above explanation it will be understood that in order to obtain an exact balancing of the circuit 14 at the particular frequency to which the resonant circuit 24 is tuned, the impedance across the terminals of the circuit 24 at this frequency must balance the impedance of the resistor 25. The tuned circuit 24 is, however, shunted by the grid-cathode impedance of the tube 20, which impedance is variable with the grid voltage, and if not decoupled from the tuned circuit tends to prevent the proper bridge circuit balance from being obtained. By providing the series resistor 20a, however, having a resistance substantially greater than the grid-cathode impedance of the tube 20, the latter impedance is rendered substantially non-effective to upset the balance of the circuit 19 at the particular frequency to which the resonant circuit is tuned, regardless of the voltage input to the bridge circuit. It has been determined that under conditions of resonance of the circuit 24, the voltage appearing across the secondary winding 26b is less than five percent of the voltage across the tuned circuit 24. When, on the other hand, the bridge circuit is excited at any frequency substantially removed from the resonant frequency of the tuned circuit 24, the voltage across the winding 26b may exceed by ten times the voltage across the tuned circuit 24. These relative values indicate the extreme sensitivity of the network to frequency deviations from the particular value to which the circuit 24 is tuned.

Although the improved signal discriminating network has been disclosed in its operation to discriminate between voice and ringing signals appearing upon the same channel of a telephone circuit, it will be understood that this network is adapted for use in any signaling system where fixed frequency and multi-frequency signals are to be received over the same signal channel, but only the fixed frequency signal is to be detected. It will also be understood that regardless of the particular system in which it is used, the action of the network is such that a false response of the detecting equipment during transmission of the multi-frequency signal is positively prevented.

While one embodiment of the invention has been disclosed, it will be understood that various modification may be made therein, which are within the true spirit and scope of the invention.

I claim:

1. In a signaling system which includes a signal channel over which may be non-concurrently transmitted a first signal having different frequencies within a frequency band or a second signal having a fixed frequency within said band, a four terminal bridge circuit coupled to said

channel and balanced at said fixed frequency, said circuit including a parallel resonant circuit in one leg thereof, a biasing resistor, thermionic means, including input electrodes bridging said resonant circuit in series with said resistor to detect a second signal appearing on said channel, and means coupled to two opposed terminals of said bridge circuit and responsive to the voltage developed across said two terminals when said bridge circuit is unbalanced for developing a bias voltage across said resistor which serves to bias said thermionic means against signal detection when a first signal appears on said channel.

15 2. In a signaling system which includes a signal channel over which may be transmitted a first signal having different frequencies within a frequency band or a second signal having a fixed frequency within said band, a four terminal bridge circuit coupled to said channel, a resonant circuit tuned to said fixed frequency and included in one leg of said bridge circuit, an adjustable impedance included in a second leg of said bridge circuit to balance the impedance of said resonant circuit at said fixed frequency, whereby the voltage developed across two opposed terminals of said bridge circuit is substantially negligible when a second signal appears on said signal channel and becomes appreciable when a first signal appears on said channel, a biasing resistor, thermionic means including input electrodes bridging said resonant circuit in series with said resistor and operative to detect a second signal appearing on said channel, means coupled to two terminals of said bridge circuit and responsive to the voltage developed thereacross for biasing said thermionic means against signal detection, thereby to prevent said thermionic means from detecting a component of a transmitted first signal having said fixed frequency, and means for preventing the input electrode impedance of said thermionic means from disturbing the balance of said bridge circuit at said fixed frequency.

45 3. In a network for discriminating between a received first signal having different frequencies within a frequency band and a received second signal having a fixed frequency within said band, a four terminal bridge circuit adapted to be excited by said signals and balanced at said fixed frequency, a resonant circuit tuned to said fixed frequency and included in one leg of said bridge circuit, an impedance element included in a second leg of said bridge to balance the impedance of said resonant circuit at said fixed frequency, whereby the voltage developed across two opposed terminals of said bridge circuit is substantially negligible when said network is excited by said second signal and becomes appreciable when said network is excited by a first signal, a thermionic tube provided with a grid and cathode bridged across said resonant circuit, means for preventing the grid-cathode impedance of said tube from disturbing the balance of bridge circuit at said fixed frequency, means including said tube for detecting a second signal impressed on said network, and means coupled to two terminals of said bridge circuit and responsive to the voltage developed thereacross for biasing said tube against signal detection, thereby to prevent said detecting means from detecting a component of a first signal having said fixed frequency.

70 4. In a signaling system which includes a signal channel over which may be non-concurrently

transmitted a first signal having different frequencies within a frequency band or a second signal having a fixed frequency within said band, a four terminal bridge circuit coupled to said channel and balanced at said fixed frequency, said circuit including a parallel resonant circuit in one leg thereof, a biasing resistor, thermionic means including input electrodes bridging said resonant circuit in series with said resistor to detect a second signal appearing on said channel, means coupled to two opposed terminals of said bridge circuit and responsive to the voltage developed across said two terminals when said bridge circuit is unbalanced for developing a bias voltage across said resistor which serves to bias said thermionic means against signal detection when a first signal appears on said channel, and means for preventing the input electrode impedance of said thermionic means from disturbing the balance of said bridge circuit at said fixed frequency.

5. In a signaling system which includes a signal channel over which may be non-concurrently transmitted a first signal having different frequencies within a frequency band or a second signal having a fixed frequency within said band, a four terminal bridge circuit coupled to said channel and balanced at said fixed frequency, said circuit including a parallel resonant circuit in one leg thereof, a biasing resistor, thermionic means including input electrodes bridging said resonant circuit in series with said resistor to detect a second signal appearing on said channel, a transformer provided with a primary winding bridged across two opposed terminals of said bridge circuit and including a secondary winding having a voltage developed thereacross in response to excitation of said bridge circuit at frequencies other than said fixed frequency, and means including a thermionic rectifier connected in series with said secondary winding and said resistor for converting said last-named voltage into a bias voltage across said resistor which serves to bias said thermionic means against detection of a first signal appearing on said channel.

6. In a signaling system which includes a signal channel over which may be non-concurrently transmitted a first signal having different fre-

quencies within a frequency band or a second signal having a fixed frequency within said band, a four terminal bridge circuit coupled to said channel and balanced at said fixed frequency, said circuit including a parallel resonant circuit in one leg thereof, a biasing resistor, thermionic means including input electrodes bridging said resonant circuit in series with said resistor to detect a second signal appearing on said channel, a transformer provided with a primary winding bridged across two opposed terminals of said bridge circuit and including a secondary winding having a voltage developed thereacross in response to excitation of said bridge circuit at frequencies other than said fixed frequency, means including a thermionic rectifier connected in series with said secondary winding and said resistor for converting said last-named voltage into a bias voltage across said resistor which serves to bias said thermionic means against detection of a first signal appearing on said channel, and means for preventing the input electrode impedance of said thermionic means from disturbing the balance of said bridge circuit at said fixed frequency.

7. In a network for discriminating between a received first signal having different frequencies within a frequency band and a received second signal having a fixed frequency within said frequency band, a four terminal bridge circuit adapted to be excited by said signals and balanced at said fixed frequency, means included in said circuit for unbalancing said circuit at frequencies other than said fixed frequency within said frequency band, thermionic means including input electrodes coupled to one leg of said bridge circuit, said thermionic means being operative to detect excitation of said bridge circuit at said fixed frequency, means coupled to two opposed terminals of said bridge circuit and responsive to the voltage developed across said two terminals when said bridge is unbalanced for biasing said thermionic means against signal detection, and means for preventing the input electrode impedance of said thermionic means from disturbing the balance of said bridge circuit at said fixed frequency.

ROBERT A. CLARK, JR.
